VANITY CASE

Winfred T. Parkin, Providence, R. I., assignor to
 Theodore W. Foster & Bros. Co., Providence,
 R. I.

Application May 31, 1934, Serial No. 728,319

6 Claims. (Cl. 132—79)

This invention relates to vanity cases, and the primary object thereof is to provide a case of this type which has a hinged cover and a lipstick preferably housed by the hinge structure, whereby upon opening of the cover the lipstick will be partially ejected so as to enable same to be gripped by the fingers of the user and bodily removed from the case, and upon completion of use may be partially reinserted and upon closing 10 of the cover completely moved within the case so as to have its said ejected portion lie flush with the adjacent portion of the case.

A further object of the invention is to provide 15 a housing for the lipstick in the hinge of the cover thereby to afford a more compact structure, and to further provide means for positively partially ejecting the lipstick out of the casing and completely back thereinto upon opening and closing movements of the cover.

20 In the drawing:

Figure 1 is a top plan view of the invention with the parts in closed position;

Figure 2 is a like view with the cover in open position showing the lipstick carrier partly ejected;

Figure 3 is a section on line 3—3 of Figure 2; and

Figure 4 and Figure 5 are sections on the lines 4—4 and 5—5 of Figure 3 respectively.

In proceeding in accordance with the present invention a casing or housing 1 is provided which may be of any desired form or shape and which has a member 2 on its bottom which latter has a curved end 3. A hollow hinge knuckle 4 is formed by curling or rolling an end of the cover 5. The cover may be provided with a mirror 6 as shown. The body has a complementary hollow hinge knuckle 4' secured thereto and over which the knuckle 4 of the cover 5 movably engages. A rouge pan 7 may be provided in the casing as shown more clearly in Figure 2, the rouge pan being removably held in position by teats 7' formed on the part 3, likewise a powder compartment closed by a hinge cover 8 may also be provided in the casing 1. The knuckle 4 is provided with an axial slot 8 in which is received a pin 9 which projects outwardly from a tubular member 10, the latter being slidably mounted in the knuckle 4. The member 10 is preferably provided with a longitudinal slit 11 whereby to enable same to frictionally grip the lipstick carrier 12, the latter having a finger engaging grip 13 at one end thereof. The slot 8 and the pin 9 hold the tubular member or sleeve against rotary movement while still permitting same to

have longitudinal movement, while the knuckle 4 has a spiral slot 14 in which the pin 9 also projects whereby it will be seen that upon opening and closing movement of the cover the sleeve 10 will be moved outwardly and inwardly respectively of the casing thereby to eject the end 13 and to retract same upon opening and closing movement of the cover. The lipstick carrier 12 also is preferably split as shown at 12' in order to increase its frictional engagements with the tube or sleeve 10.

In operations the parts are normally in the position of Figure 1, but upon opening the cover 5 the lipstick carrier will be slid longitudinally by virtue of the slot 14 and pin 9 and outwardly to the position shown in Figures 2, 3, and 4, and thus its end 13 is rendered accessible to be gripped by the fingers and the carrier entirely withdrawn from the case.

Upon reinsertion of the carrier in the case as shown in Figure 4 the inner end of the finger gripping member 13 will abut the adjacent end of the sleeve 10 and thus limit insertion of the carrier, following which the cover is closed and by virtue of the slot 14 and pin 9 the carrier will be retracted or moved inwardly into the case into the position of Figure 1 in which its part 13 lies flush with the adjacent side or wall of the case. Since the engagement between the lipstick carrier and the tube 11 is a frictional one, it will be seen that the carrier will partake of all of the movements of the sleeve 10 in opening and closing of the cover, and can be easily and quickly completely removed from the case.

What is claimed is:

1. In a vanity case, a body having a cover, means to hingedly connect the cover to the body, a lipstick carrier housed by the hinging means and bodily removable therefrom, and means operable by and upon opening and closing of the cover for moving the carrier outwardly to enable an end thereof to be gripped by the fingers and bodily removed and upon replacement and closing of the cover to be moved back into a position when the carrier lies flush with the adjacent wall of the body.

2. In a vanity case, a body having a cover, means to hingedly connect an end of the cover to an end of the body, a lipstick carrier slidably incorporated in the hinging means, and means operable by opening of the cover for partially ejecting the carrier to enable complete removal thereof and upon reinsertion of the carrier and closing of the cover for restoring the carrier to normal housed position.

3. In a vanity case having a ninged cover, a
lipstick carrier housed within and bodily removable
from the case, and means operable by and
upon operation of the cover for partially ejecting
the carrier from the case so as to enable its complete
removal and upon partial reinsertion in the
case to retract the carrier completely into the
case. 80
4. In a vanity case, a case having a movable
cover, a lipstick carrier housed within and bodily
removable from the case, and means operable by and
upon operation of the cover for partially ejecting
the carrier from the case so as to enable its complete
removal and upon partial reinsertion in the
case to retract the carrier completely into the
case. 85
5. In a vanity case, a body having a hollow
knuckle, a cover having a hollow knuckle movably
engaged with and over the body knuckle whereby
20 to provide a hinged connection between the body
and cover, a tubular member slideable in the body
knuckle, a pin, bodily receivable in a slot provided
therefor in the body knuckle to prevent turning
of the tubular member which permitting axial
sliding movement thereof, said cover knuckle having
a spiral slot in which the pin projects whereby
to slide the tubular member of the body upon
closing and opening of the cover, and a lipstick
carrier removably engaged with the tubular member
to partake of the sliding movements of the
latter. 90
6. In a vanity case, a body having a hollow
knuckle, a cover having a hollow knuckle movably
engaged with and over the body knuckle whereby
to provide a hinged connection between the body
and cover, a tubular member slideable in the body
knuckle, means to prevent turning of said member
while permitting axial sliding thereof, means operable
by movements of the cover to slide said
member, and a lipstick carrier removably receivable
in said member to partake of the movements
thereof. 95
